UNITED STATES PATENT OFFICE.

MYER H. LEBOLT, OF CHICAGO, ILLINOIS, ASSIGNOR TO MESSRS. LEBOLT & COMPANY, OF CHICAGO, ILLINOIS, A CORPORATION OF ILLINOIS.

DESIGN FOR THE CASE AND DIAL FOR A BRACELET-WATCH.

51,539.

Specification for Design.

Patented Dec. 4, 1917.

Application filed September 11, 1917. Serial No. 190,851. Term of patent 3½ years.

To all whom it may concern:

Be it known that I, MYER H. LEBOLT, a citizen of the United States, residing at Chicago, in the county of Cook and State of Illinois, have invented a new, original, and ornamental Design for the Case and Dial for a Bracelet-Watch, of which the following is a specification, reference being had to the accompanying drawings, forming part thereof.

In the drawings,

The figure is a perspective view of the case and dial for a bracelet watch embodying my design.

I claim:

The ornamental design for the case and dial for a bracelet watch, as shown.

MYER H. LEBOLT.
